UNITED STATES PATENT OFFICE.

CARL ZETTERLUND, OF CHICAGO, ILLINOIS.

HOISTING APPARATUS.

Application filed December 4, 1926. Serial No. 152,524.

My invention relates broadly to hoists or elevating machines used particularly for elevating building material and similar objects to higher levels, say in the construction of buildings, and has particular reference to a machine of this type, which is automatic in the operation of stopping the platforms or cages when reaching a predetermined level. While I shall describe my invention as being particularly adaptable for elevating building material and similar objects in the construction of a building and automatic in the manner above described, it will be understood that my invention may be used for elevating other objects, whether of similar or dissimilar nature, while on the other hand, it may embody certain features of novelty hereinafter disclosed without being automatic in the operation of stopping the movement of the platforms when reaching the desired level.

The principal object of the invention is to provide a novel form of mechanism for controlling, clutching and releasing a cable-winding drum whereby it will alternately elevate and lower a pair of elevators or cages of the apparatus, said operation being controlled at a point remote from the drum.

Other objects and advantages of the invention will be apparent from the following detailed description when taken in connection with the accompanying drawings which form a part thereof.

In the drawings:

Figure 1 is a side elevation of a machine embodying my invention;

Fig. 2 is a top plan view of the same;

Fig. 3 is a view taken on line 3—3 of Fig. 2;

Fig. 4 is a detailed view looking at one end of the drum;

Fig. 5 is an enlarged sectional view of one of the clutching elements comprising the reversing mechanism;

Fig. 6 is a fragmentary sectional view taken vertically through the center of the drum as shown in Fig. 3; and Fig. 7 is a detailed view of a portion of one of the clutching elements.

Referring more particularly to the drawings wherein I have shown a preferred embodiment of my invention, a base 10 is adapted to carry the uprights or standards 11, which are connected at the top by a cross member 12. A central standard 13 is likewise suitably carried and connected at its top to cross member 12 and between these stand-

ards the elevator cages or platforms 14 and 15 are guided for operation. The standards comprise the main supporting frames of the platforms, which frames may be of any suitable size, form and material, but preferably of wood or metal and of a height capable of reaching the desired level to which the platforms are to be elevated, in some instances to ten or more stories, which is quite common in the construction of modern sky scrapers. Supported by a top cross member 12 are the sheaves 16 and 17, about which the ends of a cable 18 are trained for connection to said platforms 14 and 15. This cable is adapted alternately to raise and lower the platforms, and, as a consequence, when one end of the cable is being wound upon a drum 19, the other end is being released, which action results in the raising of one of the platforms and in the lowering of the other.

It is apparent from Figs. 1 and 2 that both strands of cable 18 extend downwardly and under a double grooved pulley 20 suitably supported on base 10, from where said strands are wound in the usual manner around drum 19.

The power for operating drum 19 and for providing alternate rotation to lower and raise the platforms in proper sequence is obtained through a reversing mechanism carried by a continuously driven power shaft 21. This power shaft may extend from any suitable source, as at 29, and is adapted to carry at its outer end a gear 22 meshing with a pair of larger gears 23 and 24. These gears are splined to shafts 25 and 26 at their inner ends.

A U-frame 27, mounted on base 10, is adapted to support near the upper ends of its legs a transverse shaft 30. A ring gear 31 is carried on shaft 30. At one side of this gear, the drum 19 is suitably fastened so as to be driven thereby from a reversing mechanism disposed below on shafts 25 and 26. The shafts are suitably journaled in one of the walls of frame 27. Clutching elements 34 and 35 are carried by said shafts on the ends projecting into and through housing 27.

Both clutching elements 34 and 35 are substantially the same in construction. By referring to Fig. 5, it will be noted that clutching element 35 comprises a rotatable frame 36 splined to shaft 26, which frame is provided with a pair of outwardly extending parallel lugs 37 and 38 apertured to receive a spring pressed pin 39. A pulley 40 is carried against

the outside face of lug 37 on pin 39 and is adapted to be rotated by a control cable 41. The opposite end of pin 39 may be provided in the form of a latch protruding from lug 38. Between frame 36 and frame 27, a loosely mounted gear 42 is carried on shaft 26. Gear 42 is constantly in mesh with ring gear 31 on drum 19. Gear 42 is provided with an extended hub 43 from which extends a projecting lug 44. Lug 44 lies in the path of the latch end of pin 39 whereby the rotation of the clutching element will bring the pin into engagement with lug 44 to drive gear 42.

Shafts 25 and 26 rotate, of course, in opposite directions, due to being driven by the gear 22 on power shaft 21. Clutching elements 34 and 35 will also rotate in opposite directions. By forming the end of pin 39 as a latch, either clutching element may rotate without driving its cooperating lug 44 on gears 42. It will be observed that this latch end of each pin 39 is furnished with a groove 47 (Fig. 7). Pins 39 may be rotated to present groove 47 to the lugs so as to drive the gears 42. On the other hand, they may be rotated to present the slanting face 48 to the lugs 44, so that as the same engages the lugs, the pins will be displaced against the action of springs 59.

As before mentioned, a control cable 41 is furnished for the clutch element 35. A similar control cable 50 is furnished for the clutch element 34. These cables lead to a pair of levers 51 and 52. Levers 51 and 52 are pivotally mounted on the central standard 13, preferably at the level to which the platforms are elevated. I desire to project these levers inwardly so as to lie in the path of the platforms. As these platforms alternately raise, they are adapted to engage the inward projections of the levers and trip the same upwardly about their pivot points 53.

Assuming now that the lever 51 will be tripped by the platform 14 as it is raised, as shown in Fig. 1, the control cable 41 attached to the lever and clutching element 35 will be pulled upwardly. The cable is guided by a pulley 54 disposed adjacent to the clutching element as well as by a second pulley 55. From this point, the cable extends horizontally towards the clutch element 35 and about a roller pin 56 to permit it to encircle pulley 40. The cable is fixed to pulley 40. As the cable is pulled upwardly, the pulley 40 will rotate in the direction of the arrow as shown in Fig. 5. Such rotation of the pulley 40 will rotate the pin so that the groove 47 in the latch end thereof will be turned away from the lug 44, thereby presenting the angular face 48 thereto so as to cause this pin to be displaced as it rotates past the lug. Such action disengages the clutch element 35 from its gear 42 and disconnects the drive from the drum 19. With both levers 51 tripped upwardly, the hoist will be in neutral position and the drum 19

will not rotate to raise and lower either platform.

To start the hoist operating, one of the platforms is loaded. The workman at the high level then manually operates one of the levers 51 or 52, whereby the cooperating control cable 41 or 50 will be released to allow the clutch pin of one of the clutching elements to present its groove 47 to the lug 44. As long as the control cables are held taut, the clutch pins 75 will be held against rotation by the tension of coil springs 59. Placing slack in either control cable will, however, allow the corresponding spring 59 to return one of the pins to a position presenting its groove 47 to lug 44. 80 Drum 19 will now be driven in either direction, depending on the clutch element engaged.

Means may be provided to lock drum 19 against reverse rotation and thereby to lock the elevator platforms against slipping, when it is desired to hold either platform at a certain level. This mechanism comprises a jack pawl 60 pivotally mounted on the frame 27, as shown in Figs. 3 and 6. Jack pawl 60 is of the double acting type, having opposed fingers 63 and 64, on opposite sides of its pivot 65, alternately engaging teeth 61, so as to prevent back rotation of the drum 19 during the time when either clutching element may be in driving 95 relation with the drum. Accordingly, a control is provided for operating the jack pawl, which is governed by the particular control cable released. If control cable 41 is released to place clutch element 35 in driving relation with the drum, a pivoted lever 67 attached to the cable at 68 swings downwardly about its pivot point 69, whereby to raise the inner end of the lever 67 as shown at 70 in Fig. 3, so as to release finger 64 of the jack pawl 60 100 and engage finger 63 with teeth 61 on the opposite side of the pivot 65. Consequently, reverse rotation of drum 19, while clutch element 35 drives the drum, is prevented. Lever 71 having its lower end attached to a laterally projecting lug 72, carried on frame 27. I prefer to provide the jack pawl 60 with a positive snap action, whereby to assure engagement of either pawl 63 or 64 when the other is released. To accomplish this end, a lug 74 extends upwardly from the jack pawl on the inside of frame 27 and passes through a slot 75 in this frame so as to cooperate with a snap-over spring 76 attached to a point 77 115 on the outside face of frame 27. A lever 79, similar to lever 67, is furnished for control cable 50 and serves to throw the pawl 60 to the opposite side of its center when cable 50 is released.

Each of the levers may have a segment 80 associated therewith to be engaged by a ratchet pawl 81 carried by a manually operated arm 82. To release either lever 51 or 52 after they are moved to upper position, the 130

laborer grips arm 82 so as to disengage pawl 81 from segment 80.

From the foregoing description, the operation of my invention will be obvious. Assume that the machine is about to be operated to raise and lower platforms 14 and 15 in their proper order. The workman operates the arm 82 to disengage the pawl 81, whereupon either control cable 41 or 50 is released 10 to allow the corresponding clutching element to engage the drive. The drum 19 will rotate in either direction according to the clutching element engaged. The elevator platforms 14 and 15 will then be raised and lowered in alternative relation. When the ascending platform approaches the desired level, it will trip one of the levers. The drive shaft 21 is thereby automatically disengaged and the operation of the hoist stopped. The clutching elements will remain in neutral position during disengagement of the drive shaft and will not again place it in driving relation with the drum 19 until the opposite lever is manually released. Thus, the operation of the hoist is 20 automatically stopped by the attainment of high level by one of the platforms and is manually started again by actuation of one of the levers at the high level.

Without further elaboration, the foregoing will so fully explain the gist of my invention that others may, by applying current knowledge, readily adapt the same for use under various conditions of service without eliminating certain features which may properly be said to constitute the essential elements of novelty involved, which items are intended to be described and secured to me by the following claims.

I claim:

1. In a hoist of the type described including a plurality of platforms, the combination of a continuously operated drive shaft, a drum, cables leading from said drum to said platforms, reversing mechanism between said drive shaft and said drum, means for controlling said reversing mechanism according to the position of said platforms, said reversing mechanism including a pair of clutching elements, one for each platform, said clutching elements being in constant driving relation with said drive shaft and held out of engagement with said drum until released by said controlling means.

2. In a hoist of the type described including a plurality of platforms, the combination of a continuously operated drive shaft, a drum, cables leading from said drum to said platforms, reversing mechanism between said drive shaft and said drums, said reversing mechanism including a pair of spring pressed clutching elements and an operative connection between each clutching element and a point in the path of travel of each platform, said connections serving alternately to release said clutching elements

whereby to engage said drum for driving the same alternately in opposite directions.

3. In a hoist of the type described including a plurality of platforms, the combination of a continuously operated drive shaft, a drum, cables leading from said drum to said platforms, a clutching element for each platform, a control element for each platform, cables leading from said clutching elements to said control elements, said control elements being manually operable to cause said clutching elements alternately to engage said drum and automatically operable to disengage said clutching elements, said clutching elements being constantly driven by said drive shaft.

4. In a hoist of the type described including a plurality of platforms, the combination of a continuously operated drive shaft, a drum, driving connections leading from said drum to said platforms, control elements for automatically stopping said platforms when reaching a predetermined level, said control elements including lever mechanism, flexible connections leading therefrom, and a reversing mechanism between said drum and said driving shaft including gearing and two clutching elements connected to said flexible connections and alternately connecting said drum to said driving shaft for opposite rotation.

5. In a hoist of the type described including a plurality of platforms, the combination of a continuously operated drive shaft, a drum, cables leading from said drum to said platforms, and means for connecting said drum to said drive shaft for opposite rotation comprising oppositely rotating shafts in constant driving relation with said drive shaft, and a spring pressed clutching element fixed to each shaft to be rotatable therewith, loosely mounted gears on said shafts, a ring gear attached to said drum and in mesh with said gears, lugs projecting from said gears in the paths of said pins, and control means for revolving said clutching elements whereby either to permit driving engagement with said lugs or to permit displacement thereby.

6. In a hoist of the type described including a plurality of platforms, the combination of a continuously operated drive shaft, a drum, driving connections leading from said drum to said platforms, continuously rotating displaceable clutching elements driven by said drive shaft, means for alternately placing either clutching element in driving relation with said drum including engageable lugs adapted to alternately displace either clutching element as the other clutching element is in engagement to drive said drum.

7. In a hoist of the type described including a plurality of platforms, the combination of a continuously operated drive shaft, a drum, driving connections leading from said

drum to said platforms, means for interconnecting said drum to said drive shaft for alternate rotation of said drum including a ring gear and clutching elements alternately engaging said ring gear with said drive shaft, a shaft for mounting said ring gear, said drum being hollow and mounted at one side of said ring gear, teeth formed about the inner pe-

riphery of said drum, and a double acting pawl device for engagement with said teeth to prevent accidental reverse rotation of the drum when driven in either direction. 10

In witness whereof, I have hereunto subscribed my name.

CARL ZETTERLUND.
